DESIGN FOR A LACE

Bert Edson, Pawtucket, R. I., assignor to New England Lace Mills, Inc., New York, N. Y.

Application November 20, 1936, Serial No. 66,036

Term of patent 3½ years

To all whom it may concern:

Be it known that I, Bert Edson, a citizen of the United States of America, residing in Pawtucket, county of Providence, and State of Rhode Island, have invented a new, original, and ornamental Design for a Lace, of which the following is a specification, reference being had to the accompanying drawing, forming part thereof,

The figure of the drawing is a plan view of a lace showing my new design.

I claim:

The ornamental design for a lace, substantially as shown.

BERT EDSON.
